BERNARD GRANVILLE, OF NEW YORK, N. Y.

MIXING DEVICE.

Application filed November 17, 1920. Serial No. 424,609.

This application relates to devices for mixing a liquid with a gas, and has particular application to the class of such devices known as carbureters which are used in connection with internal combustion engines to mix liquid fuel with air.

An object of the invention is to provide a device in which the proportion of liquid mixed with the gas is automatically determined by the rate of flow of gas through the device.

A further object of the invention is to improve and simplify the mechanism for operating the valve controlling the admission of liquid to such a device.

When applied to the carbureters of internal combustion engines, the invention affords a means whereby the proportion of fuel vapor in the mixture drawn into the engine is automatically controlled by the speed of the engine.

According to my invention, the percentage of liquid fuel in the form of vapor mixed with the air drawn through the carbureter is regulated by a balancing of fluid pressures. The device contains no valves and no moving parts other than a float, and is thus not subject to the irregularities in action which have characterized mechanical devices for regulating the richness of the mixture. Furthermore, in accordance with my invention, the richness of the mixture may be maintained constant, or otherwise regulated, throughout the entire range of the engine speed and the device may, therefore, be so adjusted as to produce precisely the most efficient mixture at all speeds of the engine.

In carrying out the invention, I divide the liquid receptacle of the carbureter so as to provide two balanced columns of liquid. In the air passage of the carbureter I provide a Venturi tube in which the fuel nozzle is located, and a Pitot tube communicating with the liquid receptacle above one of the columns of liquid therein. Located in the other column in the liquid receptacle is a float which carries the nozzle.

In order that my invention may clearly be understood, I will describe in detail the carbureter embodying the invention which is shown in the accompanying drawings, in which:—

Fig. 1 is a sectional elevation of the carbureter;

Fig. 2 is a transverse section taken on the line 2—2 of Fig. 1;

Fig. 3 is a transverse section taken on the line 3—3 of Fig. 1;

Fig. 4 is a fragmentary section sectioned on a plane at right angles to the section plane of Fig. 1 showing a means for adjusting the position of the Venturi tube in the air channel; and

Fig. 5 is a top view of the nozzle and the float on which it is supported.

The carbureter shown in the drawing comprises a liquid receptacle 10 and an air passage 11 separated by a partition 26. The intake end 12 of the channel 11 is open to the atmosphere or, if desired, is connected by a pipe to a source of warm air. The outlet end 13 of the channel 11 is connected to the intake manifold of the engine. In the channel 11 is a butterfly throttle valve 14 of ordinary construction. From an aperture in the bottom of the liquid receptacle extends an elbow pipe 15 to the outer end of which is connected a pipe leading from a source of liquid fuel. The elbow 15 is maintained in position by a collar 16 screwed upon a boss 17 at the bottom of the carbureter. A channel 18 leads from the liquid receptacle 10 to a point in the channel 11 near the end of the butterfly valve 14. This channel is controlled by a manually operated valve 19 and serves to permit the drawing of liquid fuel directly into the upper portion of the channel 11 when the butterfly valve is almost closed, to aid in starting the engine. The parts thus far described are in common use in carbureters.

An apron 25 extends into the liquid receptacle 10 from the partition 26. The apron 25 divides the liquid in the liquid receptacle 10 into two balanced columns, an outer annular column 27 and a central column 28 of much smaller cross-sectional area than the column 27. Means are provided for maintaining constant the height or level of the outer column 27. These means include an annular float 29 in the column 27, a valve 30 controlling the admission of liquid to the liquid receptacle through the elbow 15, and two levers 31. The valve 30 is normally seated by its own weight upon a conical seat 32 in the inner end of the elbow 15. The valve is maintained in alignment with the seat by a stem 33 which enters a blind hole 34 in the elbow 15. The upper portion of

the valve 30 is provided with a transverse slot 35 (Fig. 3) in which lie the inner ends of the levers 31. The inner ends of the levers are pivoted upon a pin 36 extending 5 through the valve 30 and across the slot 35. Each of the levers 31 has at an intermediate point at its lower side an integral projection 37 which rests upon the bottom of the liquid receptacle 10 and serves as the ful- 10 crum of the lever. Each lever is provided with an upward projection 38 at the outer end of its upper side.

In the column 28 is a float 40 which extends upwardly into the channel 11 through 15 a central aperture 41 in the partition 26. The float 40 bears at its upper end a nozzle 42 containing a passage 43 which communicates with a small pipe 44 extending through the float 40 and communicating at its lower 20 end with the liquid in the liquid receptacle 10. A flange 45 (Fig. 5) maintains the lower portion of the float 40 in central position within the apron 25 so that the upper portion of the float does not bind in the aperture 41.

A Venturi tube 50 is located in the channel 11 in such position that the end of the nozzle 42 lies within it. The Venturi tube 50 is provided with a cylindrical flange 51 30 which fits within the upper portion of the channel 11. From the flange 51 projects a stud 52 which passes through a slot 53 in the wall of the channel 11 (Fig. 4). On the outer end of the stud 52 is screwed a nut 54. 35 The arrangement described permits a vertical adjustment of the Venturi tube 50 in the channel 11.

A Pitot tube 55 is screwed into a threaded hole 56 in the partition 26 above the top of 40 the column 27. The Pitot tube 55 extends into the channel 11 and its outer end 57 is directed against the current of air passing through the channel 11.

A rod 60 may be provided for manually 45 pressing down the float 29 and opening the valve 30 in order to "flood" the carburetor to facilitate starting the engine. The rod 60 may conveniently be extended into the liquid receptacle 10 through the Pitot tube 55 as shown in Fig. 1. A spring 61 maintains the rod 60 normally in raised position.

The operation of the device described is as follows:—It will be understood that before a current of air is drawn through the 55 channel 11 this channel is filled with air at atmospheric pressure. The air in the channel has free access to both the columns of liquid in the receptacle 10, reaching the column 27 through the Pitot tube 57 and the 60 column 28 through the aperture 41 in which the float 40 fits loosely. The device is placed in operation by reducing the pressure at the outlet end 13 of the channel 11, the reduction of pressure being usually caused by the 65 suction created in the cylinders of an inter-

nal combustion engine with which the device is used. Because of this reduction of pressure at the outlet end 13 the atmospheric pressure applied at the entrance end 12 of the channel 11 causes a current of air to 70 flow through the channel. As this current passes through the Venturi tube 50 its velocity is increased with a reduction of pressure so that the pressure which is applied to the top of the liquid column 28 through 75 the central opening 41 causes the liquid in the receptacle 10 to pass through the pipe 44. As the result the liquid is sprayed into the air in the Venturi tube through the nozzle 43. The rate at which liquid is projected 80 through the nozzle is, of course, dependent upon the difference between the pressure applied to the column 28 and the pressure in the portion of the Venturi tube 50 in which the nozzle 43 is located. It follows that 85 when the end of the nozzle 43 is in the narrowest portion of the Venturi tube 50 the suction and the consequent rate of flow of liquid through the nozzle is greater than when the end of the nozzle is located in a 90 wider portion of the Venturi tube. The position of the nozzle 42 in the Venturi tube is automatically determined by the rate at 95 which air is sucked through the channel 11 by the engine. The current of air through the channel 11 produces in the Pitot tube a pressure which increases as the velocity of the current increases. This pressure is applied to the top of the column of liquid 27, while the pressure applied to the top of the 100 column 28 through the central opening 41 is not increased with an increase in the velocity of the current. The difference in the pressure applied to the two columns consequently causes a difference in the height of 105 the columns, which difference is increased as the pressure increases. As the level of the column 27 is maintained substantially constant by the control of the valve 30 by 110 the float 29, the pressure results in an increase in the height of the column 28. As the liquid in the column 28 rises, the float 40 is carried upward, raising the nozzle 42. The end of the nozzle is thus brought into a 115 wider portion of the Venturi tube 50 so that the rate at which the liquid is drawn through the nozzle is maintained in exact proportion to the flow of air, maintaining constant the richness of the mixture drawn into the engine.

The height to which the level of the column 28 is raised above the level of the column 27 depends not only upon the pressure produced by the Pitot tube but also upon the relative areas of the columns. By making 125 the area of the column 28 small in comparison with the area of the column 27, wide differences in the height of the column 28 may be obtained for slight variations in the pressure produced by the Pitot tube.

It is apparent that by proper proportioning of the opening in the Pitot tube 55, the area of the columns 27, 28 and the position and shape of the Venturi tube 50, the device 5 may be arranged so as automatically to produce just the mixture desired for every velocity of flow of air through the channel 11, that is to say, for every speed of the engine. The device affords numerous advantages be- 10 sides those hereinbefore referred to. Thus the central location of the column 28 with respect to the column 27 enables the device to operate when inclined at a considerable angle to the vertical. Furthermore, the ar- 15 arrangement of the levers 31 is extremely simple and obviates the necessity of providing the levers with pivots at their fulcrum points.

It is apparent that numerous modifications may be made in the form and arrangement of the device described without departing from the scope of the invention. Among such modifications are the following: It is not essential that the Pitot tube 20 55 be located or turned as shown in the drawings, and it should be understood, therefore, that the use of the word "pressure" in the claims hereto appended is intended to include a negative pressure as well 25 as a positive pressure.

The Venturi tube may be located anywhere in the channel through which the gas passes and may be formed as an integral part of the channel instead of as a separate piece as shown. The expression "channel including a Venturi tube" used in the accompanying claims is intended to include any means whether or not integral with the wall of the channel which provides, in the channel, zones of different cross-sections at which the velocity of the current will be different.

While the combination of the Pitot and Venturi tubes eliminates all valves and produces most desirable results, either of these devices may advantageously be used separately. Thus the pressure produced by the Pitot tube may be utilized to operate a valve or otherwise control the rate at which the liquid is drawn from the receptacle 10 without the use of the Venturi tube 50. Or, on the other hand, other means than the pressure produced by the Pitot tube 55 may be used to position the nozzle 42 in different 50 55 parts of the Venturi tube 50.

While I have found the arrangement of the apron 25 and the floats 29 and 40 satis-

factory and convenient, it is nevertheless true that this arrangement may be varied as, for example, by applying the pressure 60 produced by the Pitot tube directly to the column of liquid whose height regulates the position of the nozzle 42, or by reversing the connections of the two floats. The nozzle 42 need not be borne directly upon one of the 65 floats, but may be operated by one of the floats by means of a rod or other connection.

The invention is not limited to its application to the carbureter of an internal combustion engine, but may be availed of wherever 70 it is desired to regulate the proportions of a mixture of a liquid and a gas.

What is claimed is:

1. In a device for mixing a gas and a liquid, the combination of a channel including 75 a Venturi tube through which the gas is passed, a liquid receptacle arranged to divide the liquid into balanced columns, a passage for the liquid from said receptacle to said channel, a nozzle at the end of said passage located in said Venturi tube, a Pitot tube communicating with said receptacle, extending into said channel and adapted to apply to one of said columns a pressure determined by the rate of flow of gas through 80 said channel, means for retaining the height of one of said columns substantially constant, means for varying the location of said nozzle in said Venturi tube actuated by 85 variations in the height of the other of said columns produced by said pressure.

2. In a device for mixing a gas and a liquid, the combination of a channel including 90 a Venturi tube through which the gas is passed, a liquid receptacle adapted to divide 95 the liquid into balanced columns, a passage for the liquid from said liquid receptacle to said channel, a nozzle at the end of said passage having its end located in said Venturi tube, a Pitot tube communicating with said liquid receptacle, extending into said channel and adapted to apply to one of said columns a pressure determined by the velocity 100 of flow of gas through said channel, means for maintaining the height of said column substantially constant, and a float in the other of said columns arranged to vary the position of said nozzle in said Venturi tube as the height of said column varies under the influence of said pressure.

In testimony whereof I have hereunto set my hand.

BERNARD GRANVILLE.
